TYPEWRITING MACHINE

Russell G. Thompson, West Hartford, Conn., assignor to Underwood Elliott Fisher Company, New York, N. Y., a corporation of Delaware

Application April 1, 1937, Serial No. 134,324

11 Claims. (Cl. 197—178)

This invention relates to typewriting and book-keeping machines and with regard to certain more specific features thereof to denominational tabulator mechanism adapted to be power-actuated in such machines.

In U. S. patents to McLaughlin 956,144 and Helmond 1,858,447 denominational tabulators are shown in which a row of keys are adapted for selective depression of spring-pressed levers which in turn move denominational reeds or blades at the rear of the machine into position to engage column or carriage stops set on a carriage rack. Provision is also made for releasing the carriage from its escapement when a key is depressed so that the carriage may be moved by its spring or other motor means until a set stop on the carriage engages a denominational-tabulator stop which has been moved to stop position. The present invention employs keys, levers and reeds or blades of the same general type shown in these patents but provides for the selective movement of the reeds or blades to stop position by power from an electric motor or similar prime mover and also provides for their restoration automatically at the end of the tabulating movement. The invention further provides for the restoration of any set stop by means coming into operation at the line-end or prior to carriage return so that no blade is in position to interfere with the return of the carriage.

The invention has, therefore, as one of its objects, to provide a simple, inexpensive and reliably operative device for power-actuating a plurality of denominational-tabulator stops.

Another object is to provide a simple latching mechanism for the stops which permits them to be unlatched by collision of the carriage in its tabulating travel.

Still another object is to provide a reliably operative device for clearing all stops from the return path of the carriage.

Other objects will be in part obvious and in part pointed out particularly as the description of this invention proceeds.

In the accompanying drawings wherein is shown one of various possible embodiments of the invention:

Fig. 1 is a view in side elevation, with side wall broken away in part, of a typewriting machine embodying the invention.

Fig. 2 is a view in perspective showing the denominational-tabulator mechanism shown in Fig. 1.

Fig. 3 is a view in perspective of a part of the escapement control.

Fig. 4 is a view in perspective of a part of the clearing device for the denominational-tabulator stops.

Fig. 5 is a view in perspective of the operating mechanism for the tabulator stop clearing device shown in Fig. 4.

Referring now more in detail to the drawings, a typewriting machine frame is indicated generally at 20 made up of left and right side walls 21 and 22 connected at the rear by a plate 23 and 10 at the front by the usual front bar, not shown, and an anchor bar 24. About midway between the front and rear of the machine the two side walls are connected by a backbone 25 and cross bars 26 and 27. A comb-slotted plate 29 is connected at one end to a rib 30 projecting inwardly from the side wall 21 near the front of the machine and has its other end connected to a similar rib extending inwardly from the side wall 22.

As shown clearly in Fig. 2 of the drawings, a plurality of key levers 31 are positioned for guidance in slots 32 in the plate 29. One of these levers 33 is for the purpose of setting the desired column or carriage stops as will be more fully described later, and another one of the 25 levers 34 has as its purpose the clearing of any set column or carriage stops as will be described later. The other levers 35 are the various denominational key levers having keys 36 and these levers are suitably bent at the rear of the comb plate 29 so that beyond the plate they are grouped substantially at the center of the machine in slots 37 in a flange 38 of the backbone 25. A fulcrum pin 40 passes through the flange of the backbone and through all of the levers 33, 34 and 35. The 35 comb plate 29 has a short rearwardly extending flange 41 provided with fingers 42 to which are attached ends of individual pull strings 43, the opposite ends of which are attached to hooks 44 formed on the levers 33, 34 and 35. These springs 43 serve to hold the key levers normally up in the comb slots 32 with their hook portions 44 bearing against a resilient stop member 45 suitably secured to the rear of comb plate 29 in position to present the engaging part of resilient member 45 45 suitably below the top of the comb slots. It will be understood that the various character key-levers of the typewriter are also pivoted by pin 40 in flange 38 of the backbone. Some of these key levers are indicated in Fig. 2 at 46 as between 50 the grouped denominational-tabulator levers and others are arranged in the backbone on opposite sides of the group.

The "Tab-set" lever 33 has an extension 47 rearwardly beyond the fulcrum pin 40. This ex- 55

tension is joined by a connector 48 to a lever 49 pivoted on the cross bar 27 at 50 and extending parallel to the bar. An opposite end 51 of this lever is connected by a link 52 to one end of a lever 53 pivoted on a shaft 54 which is journaled in arms 55 projecting forwardly from the rear plate 23 of the machine. The other end of lever 53 enters a slot 56 in the lower end of a magazine 57 which latter is suitably secured to the frame 10 of the machine in an aperture 58 in back plate 23.

The slot 56 of magazine 57 also receives the lower end 60 of an angle member 61 which rises in the magazine, turns forwardly and terminates in an enlarged end 62 positioned in a slot 63 of a universal plate 64 the construction and operation of which will be described later. The function of the universal plate 64 insofar as the angle member 61 is concerned is merely to provide a guide 20 for the upper end of the member 61 in an upward and forward direction of movement. A pin 65 passes across the magazine and is suitably secured therein. The angle member 61 has cam slot 66 through which pin 65 passes. The enlarged end 62 of member 61 is pivotally connected at 67 to a bail-shaped member 68 shown in Figs. 1 and 2 of the drawings by dot-and-dash lines. This bail-shaped member comprises an arm 70 extending from pivot connection 67 to a pivotal 30 bearing on a shaft 71 which latter extends across the magazine and is suitably journaled in ears one of which is shown at 72 in Fig. 2. The arm 70 passes suitably beyond its journal on the shaft 71, then turns and extends parallel with the shaft 35 and emerges, at the other side of the magazine, with a setting finger 73 having at this point another pivotal mounting on shaft 71.

The angle member 61 having its lower end above the end of the lever 53 in slot 56 is adapted 40 to be elevated whenever the "Tab-set" lever 33 is depressed. Its elevation is permitted by cam slot 66 and forward movement must necessarily take place owing to the connection with bail-shaped member 68 pivoted on shaft 71. Elevation 45 of the member 61, therefore, rocks the bail-shaped member 68 and moves the setting finger 73 rearwardly. Thus any one of a multiplicity of carriage or column stops 80 which is in line with the setting finger may be moved rearwardly 50 in a stop-carrying bar 81 extending lengthwise of the carriage. The bar is secured in arms 82 at opposite ends of the carriage.

A conventional typewriter is indicated in Fig. 1 at 83 having a carriage rail 84 mounted on anti-friction rollers 85 in a track 86 which in turn is pivotally supported upon a balancing or case-shift frame 87 permitting case-shifting movements of the carriage. The carriage is equipped with a rack 88 which is in fixed relation with its rail 84 and the teeth of which engage a pinion 90 at the upper end of a shaft 91. The latter is supported for rotation in a bracket 92 secured to the forward side of carriage track 86. A center tie 93 is considered for the purpose of this case as 65 a frame part although adapted for slight fore and aft adjustment on the frame and the center tie is apertured at 94 to receive the shaft 91 which has a lower bearing in a bracket arm 95. A carriage escapement wheel 96 is fixed on the 70 lower end of shaft 91 and is under control of dogs 97 and 98 mounted on a rocker frame 100 adapted to be rocked on the pivots 101 and 102 (see Fig. 3) to alternately engage the dogs 97 and 98 with teeth 103 of the escapement wheel 96.

The carriage 83 is under the usual tension for

operating in a letter-feed direction either by the conventional spring motor and tape connection or by other motor means. The letter-feeding movement of the carriage is controlled by the rocking of frame 100 and the dogs are disengaged from the escapement wheel 96 for tabulating operation, all as will be particularly described later herein.

For the purpose of restoring the column stops 80, which have been set into stop position by 10 operation of the "Tab-set" key and the finger 73 the "Tab-clear" key lever 34 is provided. Depression of the "Tab-clear" key raises the rear end of lever 34 which is joined by a connector 104 to one end of a lever 105, which is pivoted by a 15 stud on bar 27 in the same manner as the lever 49 of the "Tab-set" mechanism. The other end of lever 105 connects with a lever 106 pivoted on shaft 54 and having its opposite end in one of the slots 56 in the lower end of magazine 57. This 20 slot is at the extreme left of the magazine, as viewed in Fig. 2, and it receives the lower end of a reed or blade 107 which extends upwardly in the magazine and is guided in one of a plurality of slots 108 cut in a cross bar 109 extending across 25 the upper mouth of the magazine and suitably secured thereto.

At the top of the magazine a plate 110 is secured at an inclination upwardly and forwardly from the rear of the magazine. This plate is provided with a plurality of slots 111 cut parallel to the face of the plate and therefore extending at an upward angle from the rear of the magazine. The reed or blade 107 has at its lower end a slot 30 similar to the inclined slot 66 in angle member 35 61 and its upper end is inclined to fit one of the slots 111 in plate 110 of the magazine.

Thus it will be seen that raising of the rear end of lever 106 by depression of the "Tab-clear" key 40 will elevate the reed 107 in the magazine and its inclined top end plus its pin and cam slot connection will cause it to be urged forwardly. The upper end of this reed is provided with a lateral extension having a cam face 112 receding toward the left of the machine and when the reed is set 45 into stop position, as described, a return of the carriage by hand or by power from its carriage return position at the right of the machine will cause the cam face 112 to engage all of the set carriage stops 80 in its travel and return them 50 forwardly to normal positions of disengagement.

The described means of setting the carriage stops and the clearing of the same by the manual depression of keys are not claimed in themselves as any part of the present invention except as 55 these mechanisms enter into combination with the devices which will now be described to carry out in completeness the function of a denominational tabulator for a power-driven machine.

In the preferred form of this invention shown 60 in the accompanying drawings and described herein, a constantly rotating prime mover or driving member is shown. It is not intended to limit the invention as to its power operation to a constantly operating or rotating prime mover as it 65 is conceivable that the invention in many of its broader aspects is applicable to a motor means which may be intermittently energized or brought into operation by the depression of any of the denominational-tabulator keys or some 70 other key or switch, or possibly automatically energized or coupled upon the completion or during the progress of some other operation of the machine. In the form shown the prime mover is a rotating toothed shaft 120 constantly driven 75

from a source of power such as an electric motor (not shown). Teeth 121 of this rotating shaft are adapted to engage teeth 122 of a pawl 123 pivotally connected at 124 to a vertically movable driven member 125. This driven member is provided with a slot 126 at its upper end through which a pin 127 passes, and this pin may pass entirely across the machine in a rearwardly extending flange 128 of the backbone 25. The pin 10 may serve as a guide or fulcrum for a multiplicity of similar driven members or actuators for the power operation of the type-bars, the carriage-return, case-shift, back-spacer and any other function that it is desired to form by power. To 15 this end the flange 128 of the backbone is comb-slotted and each actuator, as is the case with actuator 125, is guided in one of the slots. The actuator or driven member 125 extends downwardly in the rear of a lower flange 130 of backbone 25 and a plate 131 secured to the under side of the flange and has a diagonal leg 132 forwardly extending and provided with a hook 133. This hook is connected by a spring 134 to the plate 131 which tends to hold the member 125 20 forwardly away from the drive roller, as shown clearly in Fig. 1 of the drawings.

When, however, the member 125 is swung rearwardly around the pin 127, teeth 122 of pawl 123 are engaged by the teeth of the roller 120 and 25 the assembly of actuator and pawl is moved downwardly, slot 126 riding along pin 127. A notch 135 in the upper part of the driven member receives the rounded end 115 of an arm 116 which has its other end 117 secured to the end 30 of shaft 54. Thus the shaft 54 is rocked in the direction of the arrow (Fig. 2) and carries with it spaced arms 118 and 119 suitably secured to the shaft. The ends of these spaced arms are connected by a rod 129.

When the driven member 125 is picked up by the roller 120 and moved downwardly this movement continues until a cam edge 140 engages a rounded head of an adjustable knock-off screw 141 secured in cross bar 26. Further continued 35 downward movement causes the driven member 125 to be urged forwardly until pawl 123 is disengaged from the roller whereupon spring 134 restores the driven member to its normal position shown clearly in Fig. 1 of the drawings. Thus 40 the rod 129 is oscillated each time the pawl 123 is engaged with roller 120. The mechanism just described is a common actuator for all of the denominational-tabulator stop-blades. These 45 stop-blades, indicated at 142, are in the preferred form shown ten in number and of similar configuration to the reed or blade 107 except that they do not have the lateral extensions 112. Each 50 has its lower end in one of the slots 56 at the bottom of the magazine 57 and its upper end in one of the slots 111 of the plate 110. Each reed 55 or blade 142 has a slot corresponding to the slot 66 of angle member 61, so that as any blade or reed 142 is lifted from the bottom it will rise and move forwardly in the magazine into a position to intercept any set carriage stop 80. For 60 raising the blades 142 a series of levers 143 are grouped centrally of the machine between levers 53 and 106 and the levers 143 are individually pivotally mounted on shaft 54. Each lever 143 has its forward end pivotally connected with a 65 swingable coupler in the form of an arm 144 having a hook on its lower end as indicated at 70 145. Each arm 144 is held normally with its hook 145 out of engagement with the rod or bar 129, by a connector 146 extending from one arm 75 of a bell-crank-lever 147. These levers are

mounted in a comb-slotted flange 137 of cross bar 27 on a pivot pin 138 passing through the flange. The other arm of each lever 147 is joined by a connector 148 respectively with one end 149 of each denominational-tabulator-stop key-lever 5 35. As heretofore described, each of the latter have their key-ends held upwardly against stops by springs 43, and thus, through the connections just described, the arms 144 are normally held rearwardly to an extent permitting oscillation of 10 rod 129 without engaging any of the hooks 145. When any one of the denominational-stop-lever keys is depressed its connected bell-crank-lever 147 is rocked to swing its particular connected coupler arm 144 forwardly and position the hook 15 145 thereof below bar 129. If the bar is then oscillated it will move the selected coupler 144 downwardly rocking its connected lever 143 on shaft 54 thus elevating the rear end of the lever and elevating the blade 142 positioned in the 20 same slot 56 in the magazine. Depression of a particular denominational-tabulator-stop key-lever 35 not only moves a particular coupler 144 into coupling relation with the actuating mechanism including the rod 129, but also by means of 25 hook 44 rocks a universal bar 150 which is common to all the levers 35 and institutes the operation of the actuating mechanism, as will now be described.

The universal bar 150 underlies all the hooks 30 44 of levers 35. It is fixed on a shaft 151 journaled in the opposite side walls of the machine. At the right side of the machine the shaft has a fixed arm 152 which is connected by a link 153 with a dog-carrying lever 154 having one end pivoted on pin 40. The lever 154 is suitably guided in one of the slots 37 in the backbone and its range of motion is limited by upper and lower stops 155 and 156 respectively, which stops extend between the side walls of the machine 40 35 and also serve to limit the range of motion for the various type-bar selecting levers of the machine. The lever 154 is guided in a slot 157 in the stop member 156.

Lever 154 has a lower rearwardly extending 45 arm 158 at the rear end of which is pivotally mounted at 160 a dog 161, a nose 162 of which is normally held slightly out of engagement with driven member 125 by means of a spring 159 connecting the lever to an anchor plate 163 on 50 cross bar 24. The dog 161 is normally held in a substantially horizontal position by a spring 164 connecting a forward end 165 of the dog 55 with a lug 166 formed on the arm 158 of lever 154. This spring causes the nose 162 of the dog 55 to rest upon a small coil spring 167 which extends through the comb-slotted portion of the backbone 25 and serves as a cushioning stop. From the foregoing it will be obvious that depression of any key-lever 35 will swing the universal bar 60 150 and rock lever 154 around pivot pin 40 carrying arm 158 of the lever rearwardly and engaging the nose 162 of dog 161 with the driven member 125 which will then be rocked about pivot pin 127 until teeth 122 of pawl 123 are engaged 65 with teeth 121 of roller 120. The driven member or actuator 125 will be moved down by the roller until throw-off screw 141 engages with cam face 140 which disengages the teeth and allows spring 134 to return the driven member upwardly. 70 If the key of lever 35 is held depressed a shoulder 170 on driven member 125 will engage the nose 162 of the dog in the returning movement. The dog is free to rotate on pivot 160 and will assume an inclined position with its nose 162 held on 75

shoulder 170 until such time as the pressure on the key-lever is released and spring 159 is allowed to return lever 154 to original position. When this happens the dog 161 will ride off of the shoulder 170 and spring 164 will return it to horizontal position with its nose against the spring 167.

It will be obvious from the foregoing that whichever one of the denomination-tabulating-stop levers is depressed a corresponding coupler arm 144 will be moved into position for the actuation of the particular lever 143 to which the coupler arm 144 is pivoted and following this a movement of the universal bar by the same movement of the key-lever 35 couples up the actuating mechanism to oscillate bar 129 and rock the selected one of the group of levers 143 to elevate its associated blade 142.

To hold the blade in elevated position a simple latching mechanism is provided which includes a shoulder 180 provided by notching the right side of each blade 142 as indicated clearly at 181 in Fig. 4 of the drawings. Between the slots 108 of bar 109 which extends across the mouth of magazine 57 are teeth 182 resulting from the slotting operation. As the blades 142 are elevated and moved forwardly notch 181 comes into matching position with one of the teeth 182 on bar 109 and means are provided for giving the blade a slight lateral movement at this time to snap the shoulder 180 over the tooth 182 sufficiently to hold the blade 142 elevated even though the actuator mechanism has been oscillated to its return position.

The slight lateral movement to effect latching may be from either or both of the following described means. Each blade 142 has a forwardly extending arm 183 to which is connected a return spring 184 the lower end of which is secured to an anchor clip 185 around a pin 186 that passes from one side of the magazine to the other side in ears 187. The forward ends of arms 183 underlie the universal plate 64 and this plate is itself held in down position, as shown in Fig. 1, against the ends of the arms 183 by a spring 188.

The springs 184 may be connected from the arms 183 to the clip 187 on a slight diagonal to give a bias to the blades 142 tending to urge the shoulder 180 over the tooth 182, but more particularly the action depends upon positioning the slotted plate 109 so that the grooves or slots 108 are slightly out of line with the upper and lower slots 111 and 56 of the magazine. By this means the long thin reeds 142 may be slightly flexed so that their inherent resilience is depended upon in large part to cause them to snap the shoulder 180 over tooth 182 and latch the reed.

When any denominational-tabulator stop-blade is elevated its arm 183 rotates the universal plate 64 in a clockwise direction, as viewed in Fig. 1, carrying with it an arm 190 secured to the under or rear side of the universal plate. This arm is pivotally connected at 191 with a downwardly extending link 192 which rides at its lower end on pin 65 and which carries a stud 193 positioned in a slot 194 of an arm 195 pivoted on the frame at 196. Downward movement of the link 192 occasioned by rotative movement of universal plate 64 swings the arm 195 downwardly or clockwise as viewed in Fig. 1 around its pivot 196 and against the action of a return spring 197. The arm 195 has an ear 198 which bears against a tail 200 of dog 97 of the escape-

ment mechanism. The dog is rocked by the arm 195 against the opposition of a return spring 201 to release its tooth from the escapement wheel 96, and to hold it released so long as the blade 142 remains elevated in latched position as described. This, of course, frees the carriage to the action of its motor for a tabulating run until one of the carriage stops 80 collides with the particular denominational-tabulator stop which has been latched in stop position. The force of the collision is sufficient to release the blade from its shouldered engagement with tooth 182 whereupon the blade is instantly returned downwardly by its spring 184. As the blade moves downwardly, universal plate 64 follows under the action of its spring 188, lifting link 192, swinging arm 195 in the opposite direction assisted by spring 197, which releases dog 97 to the action of its return spring 201 and restores the dog to its control of the escapement wheel. Thus the carriage is stopped in desired position and the denominational-tabulator stop is removed from the path of the carriage stops.

To avoid the possibility of interference with the return of the carriage by reason of some one or more of the denominational-tabulator stop-blades having been actuated after the last carriage stop has passed the magazine 57, an angle member 205 is arranged over the bar 109 and held in position by a keeper 206 fastened to the bar by a screw 207. The angle member 205 is suitably cut away as indicated at 208 to permit of its free lengthwise movement. The right hand end of the angle member 205, as viewed in Fig. 2 of the drawings, is provided with an ear 172 and a rod 173 projecting from the ear. This rod has a loose guide bearing in a bracket 174 projecting forwardly from the back plate 23 and toward its outer end the shaft 212 is secured in an angle member 210 which is loosely pivoted on an arm 211 which is in turn fixed on a shaft 212 suitably journaled in flanges in the back plate 23. The shaft 212 is rocked by an arm 213 which is adapted to be moved slightly under control of the carriage as it approaches its line-end. In the event that a power-driven carriage-return mechanism is used this arm may also be rocked at or about the time that the carriage commences its return movement. Whichever actuating means is used the rocking of shaft 212 will be translated into a lengthwise movement of rod 173 and angle member 205. Teeth 215 of member 205 are normally positioned over teeth 182 of bar 109 so that any set denominational-tabulator stop lies between adjacent teeth 215. Movement of angle member 205, therefore, dislodges any set blades 142 from their shouldered engagement with teeth 182 allowing return springs 184 to retract them from stop position.

Fig. 5 shows the operating mechanism for the arm 213 by which the arm is rocked slightly by a conventional margin stop 220 on the typewriter carriage. The arm 213 is connected at its free end by link 221 to another arm 222 pivoted at 223 to another arm 224 fixed on a shaft 225 journaled in flanges on the rear wall 23. The link 221 has a stop lug 226 against which the margin stop 220 strikes in the movement of the carriage to line end position. This moves the arm 213 and rocks shaft 212 to move rod 173 and dislodge blades 142 as above described.

From the foregoing description of the construction and mode of operation of the invention it will be apparent that the operator of the machine may set any number of column or carriage

stops by passing the carriage across the machine and operating the "Tab-set" key lever at desired points and that subsequently the operator may select any denominational-tabulator stop for 5 power operation by depressing any key 36 of key-levers 35. This throws in a coupling unit corresponding to the particular key actuated thus selecting it for power actuation by an actuating mechanism set in operation by the same depression 10 movement of the same key. Once a particular denominational-tabulator key-lever is depressed the operation of the machine is automatic. The selected denominational-tabulator stop is elevated and automatically latched, the 15 escapement is disconnected, freeing the carriage to the force of its motor, and upon collision of the carriage stop with the particular denominational-tabulator stop which has been set the latter is unlatched and returned to original position 20 and the carriage is simultaneously again brought under the control of its escapement.

Ordinary letter spacing escapement is effected by movement of a universal bar 216 which reciprocates a rod 217 for rocking the dog frame 100 25 on its pivots 101 and 102. In the preferred form of the invention shown in the drawings the universal bar 216 is actuated by any of a plurality of actuators on the general order of driven member 125 all of which are arranged in a row across 30 the machine and pivotally mounted on pin 127, and each of which is adapted for movement into engagement with the roller 120 by the various character key levers or space bar lever of the machine which carry dogs corresponding to dog 35 161.

What is claimed is:

1. In a machine of the character described, a frame, a motor-driven escapement-controlled carriage movable across the frame, a magazine in said frame, a group of denominational-tabulator stops normally held in said magazine out of carriage-stopping position, settable stops on the carriage, actuators respectively for the denominational-tabulator stops, coupling means for selectively coupling said actuators to a power-operated device, a plurality of denominational-stop key-levers spring held in position in the frame, means connecting said key-levers respectively to said coupling means, a universal bar movable by 40 said key-levers, a power-driven member mounted for movement by said universal bar, a power-drive element adapted to be engaged by said driven member in said movement, means connecting said driven member to an actuator for 45 a denominational-tabulator stop through a selected coupling to thereby move the stop to operative position; the foregoing being so arranged that movement of a key lever first effects the selective coupling and then causes said engagement of the driven member to move the coupled stop, and means for disengaging the driven member when the stop arrives at operative position.

2. In a machine of the character described, a frame, a motor-driven escapement-controlled 45 carriage movable across the frame, a magazine in said frame, a group of denominational-tabulator stops normally held in said magazine out of carriage-stopping position, settable stops on the carriage, actuators respectively for the denominational-tabulator stops, coupling means for selectively coupling said actuators to a power-operated device, a plurality of denominational-stop key-levers spring held in position in the frame, means connecting said key-levers respectively to said coupling means, a universal bar 50

movable by said key-levers, a power-driven member mounted for movement by said universal bar, a power-drive element adapted to be engaged by said driven member, means connecting said driven member to an actuator for a denominational-tabulator stop through a selected coupling to thereby move the stop to operative position and to release the stop as it arrives at said position, and means for latching the stop in moved position comprising a shoulder spring-moved into latching position and releasable by lateral pressure on the stop. 5

3. In a machine of the character described, a frame, a motor-driven escapement-controlled carriage movable across the frame, a magazine in said frame, a group of denominational-tabulator stops normally held in said magazine out of carriage-stopping position, settable stops on the carriage, actuators respectively for the denominational-tabulator stops, coupling means for selectively coupling said actuators to a power-operated device, a plurality of denominational-stop key-levers spring held in position in the frame, means connecting said key-levers respectively to said coupling means, a universal bar movable by said key-levers, a power-driven member mounted for movement by said universal bar, a power-drive element adapted to be engaged by said driven member, means connecting said driven member to an actuator for a 15 denominational-tabulator stop through a selected coupling to thereby move the stop to operative position and to release the stop as it arrives at said position, means for latching the stop in moved position comprising a shoulder spring-moved into latching position and releasable by lateral pressure on the stop. 10

4. In a machine of the character described, a frame, a motor-driven escapement-controlled carriage movable across the frame, a magazine in said frame, a group of denominational-tabulator stops normally held in said magazine out of carriage-stopping position, settable stops on the carriage, actuators respectively for the denominational-tabulator stops, coupling means for selectively coupling said actuators to a power-operated device, a plurality of denominational-stop key-levers spring held in position in the frame, means connecting said key-levers respectively to said coupling means, a universal bar movable by said key-levers, a power-driven member mounted for movement by said universal bar, a power-drive element adapted to be engaged by said driven member, means connecting said driven member to an actuator for a 20 denominational-tabulator stop through a selected coupling to thereby move the stop to operative position and to release the stop as it arrives at said position, means for latching the stop in moved position comprising a shoulder spring-moved into latching position and releasable by lateral pressure on the stop; and means for restoring any moved stops when the carriage is at line-end or about to return. 25

4. In a machine of the character described, a frame, a motor-driven escapement-controlled carriage movable across the frame, a magazine in said frame, a group of denominational-tabulator stops normally held in said magazine out of carriage-stopping position, settable stops on the carriage, actuators respectively for the denominational-tabulator stops, coupling means for selectively coupling said actuators to a power-operated device, a plurality of denominational-stop key-levers spring held in position in the frame, means connecting said key-levers respectively to said coupling means, a universal bar movable by said key-levers, a power-driven member mounted for movement by said universal bar, a power-drive element adapted to be engaged by said driven member, means connecting said driven member to an actuator for a 30 denominational-tabulator stop through a selected coupling to thereby move the stop to operative position and to release the stop as it arrives at said position, means for latching the stop in moved position comprising a shoulder spring-moved into latching position and releasable by lateral pressure on the stop; and means for restoring any moved stops when the carriage is at line-end or about to return. 35

5. A tabulator-stop mechanism comprising a magazine and a blade mounted for sliding movement in the magazine, said blade having a shoulder adapted to spring into latching position over a magazine part when moved to stop position, means for moving said blade to stop position, and means for unlatching the blade. 40

6. A tabulator-stop mechanism comprising a magazine and a blade slidably mounted in the magazine, said blade having a shoulder adapted 45

to spring into latching position over a magazine part when moved to carriage-stopping position, means for moving said blade to carriage-stopping position, and means including a stop on the carriage for unlatching the blade.

5. 7. A tabulator-stop mechanism comprising a blade, means for slidably mounting said blade, means for moving said blade to a carriage-stopping position, a latch mechanism comprising a part in fixed relation to said mounting means, and means for laterally urging the blade, when moved to carriage-stopping position, into shouldered engagement with said part.

10. 8. A tabulator-stop mechanism comprising a blade, means for slidably mounting said blade, means for moving said blade to a carriage-stopping position, a latch mechanism comprising a part in fixed relation to said mounting means, means for laterally urging the blade, when moved to carriage-stopping position, into shouldered engagement with said part, and carriage-operated means for engaging said blade in an opposite lateral direction for unlatching the blade.

15. 9. A denominational - tabulator mechanism comprising a frame, a group of selectively movable blades in said frame each having a shoulder adapted to spring into latching position with said frame when a blade is moved to carriage-stopping position, means for moving said blade selectively to carriage-stopping position wherein the selected blade is adapted for release from said shouldered engagement by impact of the

carriage, and a line-end release device embracing all of the blades so as to be effective to release the shouldered stops when the carriage reaches the end of a line of travel and before return.

5. 10. In a typewriter having a movable paper carriage, a denominational-tabulator mechanism comprising a group of selectively movable stops, key levers for selectively adapting said stops for power actuation, power means for moving any adapted stop to stop position, means for latching the stops in stop position and permitting release of a stop as the paper carriage banks against it in letter-feeding direction, and another stop-releasing device automatically operative to insure release of all of the stops from the latching means prior to return of the paper carriage.

10. 11. In a typewriter having a movable paper carriage, a denominational-tabulator mechanism comprising a group of selectively movable stops, key levers for selectively adapting said stops for power actuation, power means for moving any adapted stop to stop position, a latching device comprising a plurality of shoulders and means for urging the moved stops over said shoulders and holding them there until the carriage banks against them, and means operative at the line end of carriage movement to positively dislodge the stops from said shoulders.

RUSSELL G. THOMPSON.

CERTIFICATE OF CORRECTION.

Patent No. 2,185,742.

January 2, 1940.

RUSSELL G. THOMPSON.

It is hereby certified that error appears in the printed specification of the above numbered patent requiring correction as follows: Page 5, second column, line 55, claim 4, for "power-driven" read power-drive; and that the said Letters Patent should be read with this correction therein that the same may conform to the record of the case in the Patent Office.

Signed and sealed this 30th day of January, A. D. 1940.

(Seal)

Henry Van Arsdale,
Acting Commissioner of Patents.
